SEALED IGNITION UNIT

Charles E. Wolfenbarger, Walla Walla, Wash.

Application June 30, 1949, Serial No. 102,171

5 Claims. (Cl. 123—148)

1

My invention relates to improvements in a sealed ignition unit for use in the ignition systems of internal combustion engines.

It is the purpose of my invention to provide an ignition unit of simple, compact construction which embodies a small removable coil unit which makes direct physical contact with the rotor, a shell of insulating material housing the coil unit and having the high tension distributor terminals and leads therefor embedded therein, the shell having rubber cushion seals in the top thereof for the leads to the primary coil of the coil unit and spark terminals, complementary to the shell.

My improved sealed ignition unit can readily be fit to any conventional distributor base with only minor alterations. The condenser points, and automatic spark advances are all conventional and are mounted in relation with the distributor base.

Another object and advantage of my invention is providing an ignition unit wherein all of the wiring that must extend to the unit projects compactly from the top of the unit. The wire outlets such as the spark plug wires and the battery lead for the primary winding are of the conventional type but are so mounted that they are clamped between the main body of the unit and a thin cap that fastens down over it. The wire outlets slope downwardly toward the point where they leave the unit so as to prevent any possible chance of water settling at the openings and seeping in.

The nature and advantages of my invention will appear more fully from the following description and the accompanying drawings illustrating a preferred form of the invention. It should be understood however, that the drawings and description are illustrative only and are not to be considered as limiting the invention except insofar as it is limited by the claims.

In the drawings:

Figure 1 is a view in side elevation of an ignition unit embodying my invention;

Figure 2 is a sectional view taken vertically through the ignition unit with the top of the distributor base broken away to illustrate the manner in which the unit seats on the base;

Figure 3 is a top plan view of the ignition unit with the cover removed;

Figure 4 is a bottom plan view with the shaft connection to the rotor shown in section;

Figure 5 is an exploded view taken on the line 5—5 of Figure 2 with the cover removed and the shell of the unit separated from the distributor base. The removable coil is shown partly lifted out in this figure;

2

Figure 6 is a fragmentary view in side elevation taken substantially on the line 6—6 of Figure 3;

Figure 7 is a fragmentary sectional view taken on the line 7—7 of Figure 3; and

Figure 8 is a plan view of the distributor base. Referring now to the drawings in detail the shell is illustrated at 1. It is preferably constructed of a light water proof insulating material such for example, as a hard rubber composition. The shell is open at both ends. A cover 2 closes the top end of the shell and is sealed to the top end of the shell by two gasket seals 3 and 4. The seals 3 and 4 are suitably channeled to receive a battery wire 5 and the spark plug wires 6. It will be noted from Figures 2 and 7 that both the cover 2 and the shell 1 have their facing surfaces at 7 and 8 where the wires enter sloping downwardly toward the exterior so that when the seals 3 and 4 are clamped on the wires there is no tendency for water to settle around the wires at the inlet and to seep in along the wires. The top seal 3 extends all the way around the cover so as to make the cover to shell connection water tight. The cover is secured in place by means of two bolts 9 and 10 (see Figure 5) that are embedded in the top of the shell 1 and wing nuts 11 and 12.

The lower end of the shell 1 has a dome like cavity 13 in which the high tension terminals 14 are exposed. These terminals are connected by wire leads 15 that are embedded in the shell 1 to sockets 16 that are exposed at the upper end of the shell to receive the standard conventional connecting ends 17 on the spark plug wires 6.

The cavity 13 is surrounded by a rib 18 that fits down inside a distributor base 19. A metal band 20 is provided around the lower end of the shell 1 and has slotted ears 21 and 22 to receive the securing bolts 23 and 24 which are pivoted in ears 25 and 26 on the distributor base. Wing nuts 27 and 28 are provided for the bolts 23 and 24. To complete the water tight seal, a thin rubber gasket 29 is mounted around the rib 18 to receive the upper end of the distributor base 19. A removable coil unit 30 seats in the hollow interior of the shell 1. The coil unit 30 carries a core 31, a primary winding 32 and a secondary winding 33. The primary winding 32 is led out through the top 34 of the coil unit and is electrically connected to a terminal screw 35 having a wing nut 36 to clamp the wire 5 in place for establishing current supply to the primary winding 32 from the battery of the engine.

A central opening 37 connects the hollow interior of the shell with the dome shaped cavity

13. The coil unit has a reduced portion 33 that seats in the opening 37 and a spring pressed contact 39 is mounted in the portion 33. One terminal of the secondary winding 33 is connected to the contact 39. The shell has a socket 40 offset from the opening 37 from the bottom of which an embedded wire lead 41 extends to a spring pressed contact 42 that opens into the cavity 13. The coil unit has a projecting tubular portion 43 that extends into the socket 40. The portion 43 carries a spring pressed contact 44 for making contact with the wire lead 41 in the bottom of the socket 40. The contact 44 is connected to both the primary 32 and the secondary winding 33 so as to establish electrical connections from these windings to a terminal 45 in the distributor base.

The terminal 45 as shown in Figure 8 is connected by a wire lead 46 to a condenser 47 in the distributor base. It is also connected through points 48 to a grounded post 49 to complete the primary circuit.

The distributor base 19 has a plate 50 seated in the top thereof for mounting the condenser 47, the points 48 and the contact terminal 45. The terminal 45 is of course, insulated from the base plate 50. A breaker arm 51 is also insulated from the base 50 and has a cam finger 52 for engaging a cam 53. The cam 53 is mounted on a shaft 54 which supplies power from the engine to the distributor.

The shaft 54 also mounts a rotor 55 which has a contact plate 56 secured thereon in position to be engaged by the spring pressed contact 39. The plate 56 cooperates with the terminals 14 to distribute the high tension current to the several spark plug wires 15.

When current flows into the primary winding 32 from the battery over the wire 5 it is carried through spring contact 44 and wire lead 41 to the spring contact 42 and the terminal 45 then to the points 48 and to ground. When the current flows through the primary winding 32 it induces the high potential in the secondary winding 33. The high potential current flows from the secondary winding 33 through the spring contact 39 to the plate 56. When the rotor 55 rotates, this plate distributes the high potential current to the terminals 14 within the cavity 13. Current flows through the wires 15 and the spark plug wires 6 to the engine. The circuit for the secondary coil is completed through ground and the distributor base to the ground post 49 and over the same circuit as the primary winding to the contact 44.

It will be apparent from the foregoing description that I have provided a sealed ignition unit in which all of the wires are positively sealed against dirt and moisture where they leave the unit. This is established by the seals 3 and 4. All of the wires project from the top of the unit in a compact body. The arrangement of the wire outlets at the very top of the unit permits the use of shorter high voltage wires leading to the spark plugs and helps to keep the wires away from the heat, oil and dirt from the engine. The downward sloping of the wire outlets from the ignition unit avoids any possibility of water seeping into the unit.

Another distinct advantage of my improved ignition unit is the construction of the removable coil unit which makes direct physical contact with the rotor. A defective coil can be removed with ease and replaced quickly since it makes direct physical contact with the rotor and its

5 spring contact 39 rides on the rotor. The contact resistance is very low and high efficiency in the electrical circuit is obtained. The coil unit can be taken out and replaced without any special tools or experience. It can only be put in the right way. To test the coil it is simply removed from the shell 1 with the battery wire 5 attached. Then with the engine switch on the current terminal 44 is touched against the engine and the high voltage terminal 39 is held about one quarter of an inch from the engine. If the coil is working properly a hot spark will jump from the high voltage terminal to the engine.

10 It will be noted that the rotor 55 is so constructed as to be substantially balanced. All of the parts carried by the distributor base 19, including the rotor, are readily accessible for inspection or cleaning, or for replacement by the removal of the shell 1. No wires have to be disconnected and none of the parts of the shell are loose so that they might be lost.

15 Having thus described my invention, I claim:

1. An ignition unit for internal combustion engines adapted to mount on a distributor base having a rotor, said unit comprising a two part shell 20 having an upper open topped coil receiving chamber and a lower, downwardly opening, dome-shaped cavity adapted to receive the rotor, and having a central passage connecting the chamber and the cavity, a coil unit removably seated in said chamber comprising a core and primary and secondary windings and a housing supporting the core and windings, said housing having a reduced lower end portion extending into said passage, and carrying a spring pressed contact which extends into said cavity to engage the rotor.

25 2. An ignition unit for internal combustion engines adapted to mount on a distributor base having a rotor, said unit comprising a two part shell 25 having an upper open topped coil receiving chamber and a lower, downwardly opening, dome-shaped cavity adapted to receive the rotor, and having a central passage connecting the chamber and the cavity, a coil unit removably seated in said chamber comprising a core and primary and secondary windings and a housing supporting the core and windings, said housing having a reduced lower end portion extending into said passage, and carrying a spring pressed contact which extends into said cavity to engage the rotor, a cover 30 for said shell, sealing means between the cover and the shell, said shell and said cover having outwardly projecting downwardly sloping portions with seals thereon cooperating to clamp a battery wire and spark plug wires therebetween.

30 3. An ignition unit for internal combustion engines adapted to mount on a distributor base having a rotor, said unit comprising a two part shell 30 having an upper open topped coil receiving chamber and a lower, downwardly opening, dome-shaped cavity adapted to receive the rotor, and having a central passage connecting the chamber and the cavity, a coil unit removably seated in said chamber comprising a core and primary and secondary windings and a housing supporting the core and windings, said housing having a reduced lower end portion extending into said passage, and carrying a spring pressed contact which extends into said cavity to engage the rotor, the shell having a socket in the chamber offset from said passage, the shell also having a spring pressed contact projecting into the dome-shaped cavity, a wire embedded in the shell connected to the last named contact and having a terminal in

the base of said socket, and a projection on the coil unit extending into the socket and carrying a spring pressed contact for engaging the wire terminal.

4. An ignition unit for internal combustion engines adapted to mount on a distributor base having a rotor, said unit comprising a two part shell having an upper open topped coil receiving chamber and a lower, downwardly opening, dome-shaped cavity adapted to receive the rotor, and having a central passage connecting the chamber and the cavity, a coil unit seated in said chamber comprising a core and primary and secondary windings and a housing supporting the core and windings, said housing having a portion extending through the passage and provided with a contact to rest on the rotor.

5. An ignition unit for internal combustion engines adapted to mount on a distributor base having a rotor, said unit comprising a shell having an upper open topped chamber and a lower, downwardly opening, dome shaped cavity, said shell having a small central passage extending downwardly from the chamber to the cavity, a coil unit housing having a lower portion seated

5
10

in the bottom of said chamber and having a reduced end extending through the central passage into the cavity, the coil unit housing having a core and primary and secondary windings therein, a spring pressed contact carried in the reduced portion of said housing and extending into said cavity to engage the rotor and a cover for said shell, the cover and shell having downwardly and outwardly sloping channels provided with seals to clamp battery and spark plug wires therebetween.
